UNITED STATES PATENT OFFICE.

MARY ELIZEBETH HAYMES, OF MEMPHIS, TENNESSEE.

KENNEL STRUCTURE.

1,174,861.

Specification of Letters Patent. Patented Mar. 7, 1916.

Application filed July 7, 1915. Serial No. 33,581.

To all whom it may concern:

Be it known that I, MARY E. HAYMES, a citizen of the United States, residing at Memphis, in the county of Shelby and 5 State of Tennessee, have invented new and useful Improvements in Kennel Structures, of which the following is a specification.

This invention relates to improvements in kennel structures especially adapted for use 10 in railway apartment kennel cars and consists in the construction, combination, and arrangement of devices hereinafter described and claimed.

In the accompanying drawings: Figure 15 1 is a horizontal sectional view of a railway apartment kennel car constructed in accordance with my invention. Fig. 2 is a partial vertical longitudinal sectional view 20 of the same on the plane indicated by the line *a—a* of Fig. 1. Fig. 3 is a vertical transverse sectional view of the same. Fig. 25 4 is a detail front elevation of two of the kennels. Fig. 5 is a detail end elevation of one of the kennels.

25 The body of the closed car is indicated at 1 provided with doors 2 at the ends. In one corner of the car is a toilet compartment 3 and in each of the other corners is an upholstered seat 4 which may be used 30 also as lounging beds by kennel porters. In opposite sides of the car, near the ends thereof are windows 5. In opposite sides of the car are kennels 6—7 of which any suitable number may be used and which may 35 be of any suitable size, an aisle or passage-way *Z* being formed longitudinally through the car and between the oppositely arranged series of kennels. The kennels 6 are for small dogs and the kennels 7 are for large

40 dogs. The front or inner side of each kennel or kennel apartment consists of a base board, a guide and space bar, a top bar, slats, and a sliding door. The base board of each kennel 6 is indicated at 8. This 45 base board has parallel upper and lower sides. The upper side is continuous and the guide and space bar 9 is secured on the outer side of the base board at a suitable distance from the upper edge thereof, the 50 slats 10 connecting the said guide and space bar and the top bar 11 and being spaced a suitable distance apart for the admission of light and air. A door opening 12 is formed in the slatted front side of each kennel or

55 kennel apartment. The door 13 is a longitudinally movable board, the lower edge of which rests on the upper edge of the guide and space bar 9, the width of the said door being such that it extends upwardly above the base board and to within a short distance of the top bar 11 and the said door or sliding door board is held in place and is arranged to operate between the upper portion of the base board 9 and the inner sides 60 of the slats 10. By moving this door lengthwise from left to right, it may be caused to uncover the door opening 12 to permit a dog to enter or leave the kennel and the door may be closed by moving it in the opposite direction, as will be understood. 65

The base board 14 of each kennel or kennel compartment 7 which is for a large dog, has a substantially semi-circular recess 15 in its upper side at its center, under and in effect forming a portion of the door opening 16 between the sets of slats 17. The guide and space bar 18 is secured on the outer side of the base board 14 at a point slightly below the bottom of the recess 15, the lower 75 end of the said slats being secured on the outer side of the said guide and space bar so that they are spaced from said base board and the upper end of said slats being secured to the top door 19. A door or door board 20 is arranged to slide between the slats and the base board and to rest on the guide and space bar 18. When this door or door board is in open position or uncovers the recess 15 as well as the door opening, a 80 large dog is enabled to enter or leave the kennel or kennel apartment. The door may be closed by moving it in the reverse direction, as will be understood. 85

90 I claim:

95 A kennel provided with a front wall comprising a base board, a top bar, a guide and space bar on the outer side of the base board at a point between the upper and lower sides 100 of said base board, slats having their upper ends secured to the top bar and their lower ends secured on the outer side of said guide and space bar, whereby the lower portions 105 of the slats are spaced from said base board, the slats being so arranged as to form a door opening in the said side of the kennel and a longitudinally slidable door arranged to operate on the upper side of the said guide

and space bar and between the upper portion of said base board and the inner sides of said slats, the said base board having a recess in its upper side corresponding with 5 and forming an enlargement of the door opening.

In testimony whereof I affix my signature in presence of two witnesses.

MARY ELIZEBETH HAYMES.

Witnesses:

A. J. CALHOUN,
JAS. D. COLLIER.
